UNITED STATES PATENT OFFICE.

CHARLES E. BUCKLEY, OF NEW BEDFORD, MASSACHUSETTS, ASSIGNOR TO CROMPTON & KNOWLES LOOM WORKS, OF WORCESTER, MASSACHUSETTS, A CORPORATION OF MASSACHUSETTS.

LOOM DOBBY.

Application filed April 27, 1923. Serial No. 635,116.

This invention applies to a loom dobby and relates particularly to improved devices for starting and stopping an auxiliary pattern cylinder. Dobbies having such auxiliary pattern cylinders are used in weaving handkerchiefs and similar articles in which a cross border or other special design is woven at repeated points in the length of the fabric.

10 My invention is shown as applied to a loom in which a main and an auxiliary pattern cylinder are mounted on a single axis and in which the main cylinder is actuated by continuously operating driving mechanism while the auxiliary pattern cylinder is operated only at intermittent periods.

It is the general object of my invention to provide improved operating connections by which the starting and stopping of the 20 auxiliary pattern cylinder is controlled.

My invention further relates to details of construction and arrangements and combination of parts which will be hereinafter described and more particularly pointed out in 25 the appended claims.

A preferred form of my invention is shown in the drawings, in which

Fig. 1 is a partial side elevation of a loom dobby embodying my improvements;

30 Fig. 2 is a sectional plan view taken along the line 2—2 in Fig. 1;

Fig. 3 is a sectional elevation of the pattern cylinder and supporting shaft; and

Fig. 4 is a detail side elevation showing 35 certain of the parts found in Fig. 1 but in a different position.

Referring to the drawings, I have shown parts of a dobby frame 10, one side of which provides a bearing 11 for a cylinder shaft 12. The other side of the frame 10 provides a bearing 13 for a sleeve 14 within which the shaft 12 is freely rotatable. A main or continuously operated pattern cylinder 15 is secured to the shaft 12 in any convenient 40 manner as by a clamping screw 16 and an auxiliary or intermittently operated pattern cylinder 17 is similarly secured to the sleeve 14 by a clamping screw 18. The shaft 12 is rotated by means of a worm gear 19 and worm 20, the latter being continuously rotated by a driving shaft 21.

Pattern chains 22 and 23 are mounted in the usual manner on the cylinders 15 and 17 and are shown herein as of the double index

type fully disclosed and described in the 55 prior patent to Davenport and Bardsley, No. 691,608, issued Jan. 21, 1902. The worm 20 is preferably of the dwell type and when used with a double index chain may be actuated by the driving mechanism shown and 60 described in the Davenport and Bardsley patent. The main cylinder 15 may, however, be used for single indexing by making the necessary and customary changes in the pattern chain and driving connections and my 65 invention is equally applicable to either construction.

A ratchet wheel 24 is secured to the outer end of the sleeve 14 and a feed pawl 25 is provided for advancing the ratchet wheel, 70 the pawl being pivotally mounted at 26 on the usual rocking lever 27. The feed pawl 25 is provided with a stud 28 projecting over a substantially horizontal link 29. The link 29 is provided at one end with a slot 30 through 75 which extends a stud 31 fixed on the free end of a lever 32 pivoted at 33 to the frame 10.

The lever 32 is positioned for engagement by a special ball or projection 34 on the pattern chain 23 of the auxiliary pattern cylinder 17. The opposite end of the link 29 is pivoted at 35 to an arm 36 secured to a cross bar 37 pivotally mounted in the side members of the frame 10. An arm or lever 38 is secured to the bar 37 near its opposite end 85 and is positioned for engagement by a special projection 39 on the pattern chain 22 of the main cylinder 15.

It will be understood that the pattern chains 22 and 23 are provided with the usual 90 pins 40 co-operating with dobby fingers 41 for the cylinder 15 and fingers 42 for the cylinder 17.

Having described the construction of my improved dobby mechanism, the method of 95 operation thereof is as follows:

Under normal conditions the parts are positioned as shown in Fig. 4, with the auxiliary pattern cylinder 17 at rest and the projection 34 holding the lever 32 and link 29 100 in raised position, thus preventing engagement of the pawl 25 with the ratchet 24. The cylinder 15 and pattern chain 22 operate continuously until the projection 39 engages the lever 38, raising said lever and 105 rocking the shaft 37 to lower the pivot 35 which connects the arm 36 to one end of the link 29. The link 29 is thus lowered suffi-

ciently so that the pawl 25 may engage the ratchet 24 and intermittently advance the pattern chain 23. The first advance movement of the chain 23 removes the projection 34 from beneath the lever 32, allowing the left hand end of the link 29 to drop and permitting the pawl 25 to continue in operative engagement with the ratchet 24, even after the projection 39 is removed from supporting position under the arm 38 by the next feeding movement of the pattern chain 22.

The parts are then in the operative relation shown in Fig. 1 and the two cylinders continue to rotate together until the projection 34 returns to operative engagement with the arm 32, when the pawl 25 is raised out of contact with the ratchet 24 and so remains until the projection 39 again engages the arm 38.

I have thus provided a simple mechanical connection by which the auxiliary pattern cylinder may be periodically placed in operation and will be automatically stopped after a single run of the pattern chain.

My invention has been found particularly useful in the weaving of handkerchiefs and other articles in which a cross border is frequently inserted.

Having thus described my invention, I do not wish to be limited to the details herein disclosed otherwise than as set forth in the claims but what I claim is:—

1. In a loom dobby, a main cylinder and an auxiliary pattern cylinder rotatable about the same axis, a separate dobby pattern chain on each cylinder, means to regularly advance the main cylinder and chain, additional driving mechanism for periodically advancing said auxiliary cylinder and chain, and devices controlled by said main cylinder effective to render said additional driving mechanism operative, said mechanism comprising a ratchet and a normally inoperative feed pawl for said auxiliary cylinder, and said devices comprising a lever, a pattern chain on said main cylinder effective to move said lever, and connections between said lever and said pawl through which said lever may render said pawl operative.

2. In a multiplier, a main cylinder and an auxiliary pattern cylinder rotatable about the same axis, a separate dobby pattern chain on each cylinder, means to regularly advance

the main cylinder and chain, additional driving mechanism for periodically advancing said auxiliary cylinder and chain, and devices controlling said additional driving mechanism, said mechanism comprising a ratchet and a normally inoperative feed pawl for said auxiliary cylinder, and said devices comprising a lever, a pattern chain on said main cylinder effective to move said lever, connections between said lever and said pawl through which said lever may render said pawl operative, and means controlled by said auxiliary cylinder effective to maintain said pawl operative and to thereafter render said pawl inoperative.

3. In a multiplier, a main cylinder and an auxiliary pattern cylinder rotatable about the same axis, means to regularly advance the main cylinder, additional driving mechanism for periodically advancing said auxiliary cylinder, and devices controlling said additional driving mechanism, said mechanism comprising a ratchet and a normally inoperative feed pawl for said auxiliary cylinder; and said devices comprising a link engaging said pawl, a support for one end of said link positioned by a pattern chain on said main cylinder, and a support for the other end of said link positioned by a pattern chain on said auxiliary cylinder.

4. In a multiplier, a main cylinder and an auxiliary pattern cylinder rotatable about the same axis, means to regularly advance the main cylinder, additional driving mechanism for periodically advancing said auxiliary cylinder, and devices controlling said additional driving mechanism, said mechanism comprising a ratchet and a normally inoperative feed pawl for said auxiliary cylinder, and said devices comprising a link engaging said pawl, a support for one end of said link, a rod on which said support is fixed, a lever on said rod, a pattern chain on said main cylinder effective to move said lever to render said pawl operative, a support for the other end of said link, and a pattern chain on said auxiliary cylinder effective to maintain said pawl operative and to thereafter render said pawl inoperative.

In testimony whereof I have hereunto affixed my signature.

CHARLES E. BUCKLEY.
